METAL AWNING

Hugh M. Manley and Jesse R. Faulkenberry,
Huntsville, Ala.; said Faulkenberry assignor to
said Manley

Application March 12, 1948, Serial No. 14,434

1 Claim. (Cl. 20—57.5)

1

This invention relates to a metal awning and has for an object the provision of an awning of the character designated which shall be simple and sturdy of construction and easily erected from stock parts.

Our invention contemplates a metal awning construction in which roof panels are formed from sheet metal with flanges bent over to interlock with the flanges of adjacent panels and which may be assembled by an endwise sliding movement of one panel with an adjacent panel.

A further object of our invention is to provide a metal awning embodying interlocking roof and side panels, and means for mounting the same whereby there is a circulation of air under and around the panels.

An awning embodying features of our invention is illustrated in the accompanying drawings, forming a part of this application, in which:

Fig. 1 is a side elevation of the awning showing it attached to a building;

Fig. 2 is a partial front elevation thereof;

Fig. 3 is a partial rear elevational view thereof; drawn to a larger scale;

Fig. 4 is a sectional view taken along the line IV—IV of Fig. 2 and showing one of the cover panels broken away;

Fig. 5 is a sectional view, drawn to a larger scale, and taken along the line V—V of Fig. 4;

Fig. 6 is a sectional view taken along the line VI—VI of Fig. 2; and,

Fig. 7 is a perspective view of a clip used to mount the side panels on the frame.

Referring now to the drawings for a better understanding of our invention, our improved awning comprises a roof frame consisting of downwardly sloping rafters 10 and 10' arranged, one on each side, and joined together by a top plate 11 at their upper ends, and a bottom plate 12 at their lower ends, the plates 11 and 12 being preferably in the form of channels. Joined to the lower plate 12 and extending rearwardly therefrom, at each side of the awning, are horizontal frame members 13 and 13'. The rafters 10 and 10' and the horizontal members 13 and 13' are joined at their rearward ends to the building indicated by the numeral 14.

Mounted on the frame just described is a roof comprised of outer or side panels 16, only one of which is shown, and which extend out laterally beyond the rafters 10 and 10', and are provided with downturned flanges 17 along their outer edges. Between the side panels 16 are a plurality of intermediate panels 18 and 19. The sides of the panels 18 are provided with down-

2

turned flanges 21 and 22 which are bent over and upward as shown at 23 and 24 to form hooks in cross section. The inner edges of the side panels 16 and both edges of the intermediate panels 18 are turned upwardly as shown at 26 and thence over downwardly as shown at 27 to form hooks in cross section which engage the hooks formed by bent portions 21 and 23 of the panels 18. In assembling the roof, the bent over portions are engaged and interlocked as shown in Fig. 3 by relative endwise movement of the panels. The upper ends of the panels are covered by means of a flashing strip 28 which is secured to the building at 29. The panels 16 and 19 are secured to the upper plate 11 by means of short bolts 31 which are covered by the flashing strip 28, while the panels 18 are secured by an occasional bolt 32 which passes also through the flashing strip 28. Only sufficient bolts 32 are used as are necessary to hold down the flashing strip 28 in order to limit the number of bolts exposed to the weather.

The lower ends of the roof panels 16, 18 and 19 are bent downwardly as shown in Figs. 1 and 4 to form a valance 33. The portions of the panels 16 and 19 forming a part of the valance 33 are provided with outturned flanges 34 and 36, as shown in Fig. 6, while the portions of the intermediate panels 18 forming a part of the valance are provided with inturned flanges 37, which cooperate with, and cover the outturned flanges 34 and 36 of the other panels. All of the portions of the panels forming the valance are secured to the lower plate 12 by means of bolts 38 and 39.

Along the sides of the awning are a plurality of panels 40 the upper ends of which are cut to a slope to fit under the downturned flanges 17 of the side panels 16 and are joined thereto by means of short bolts 41. Each of the side panels 40 along one edge, is turned inwardly at 42 and then parallel with the main body of the panel at 43 and is secured along that portion of the panel by means of a bolt 44 to the horizontal frame member 10, 10', 13 or 13', as the case may be. The other edge of each of the panels 40 is turned inwardly at an acute angle as shown at 45 and is secured in spaced relation with respect to the horizontal frame members 13 and 13' and with respect to the adjacent edge portion 43 of the adjacent panel, by means of a clip 46. The clip 46, as shown in Fig. 7, is comprised of a hook portion 48 which hooks over the upturned flange 49 of the frame members 13 and 13'. A horizontal portion 51 of the clip is provided with slits 52 which are cut in that portion at an angle to

receive the inturned portions 45 of the panels 40. The outer end of each of the clips is turned down as shown at 53 to provide a bearing against the inner side of the panel and hold it firmly in place.

As shown more clearly in Fig. 4 of the drawing, the rafter members 10 and 10' and the horizontal members 13 and 13' extend rearwardly a slight distance beyond the side panels 40 and the roof panels, to provide a ventilating space 54 between the body of the awning and the building. Also it will be seen that the roof panels stop short of the building to provide an exit space 56 for air currents flowing upwardly underneath the awning roof, as indicated by the arrows. Also, as indicated in Fig. 4 of the drawing, the arrangement of the cover panels and intermediate panels 19 is such as to form channels for conducting air currents upwardly underneath the roof to escape through the space 56. It will further be seen that the means for securing the side panels 40 to the horizontal member 13 and 13' and to the roof panels 16 provides spaces for the circulation of air laterally under the awning roof.

From the foregoing it will be apparent that we have devised an improved metal awning which is simple of design, easy to assemble, sturdy of construction, and one which provides for the maximum of comfort for the user.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claim.

What we claim is:

A metal awning embodying a roof frame comprising sloping rafters at the ends thereof joined at the upper and lower ends by transversely ex-

tending top and bottom plates, horizontal side plates joined to the bottom plate and extending rearwardly, upturned flanges on the side plates, a roof for the awning frame, side panels for the awning joined at their upper ends to the sloping rafters and each having a flange along one side turned inwardly and thence laterally, means connecting the laterally turned portions of said flanges to the upturned flange of the associated side plate, and clips joining the opposite side of each side panel to the flange of said side plate and holding the said opposite side in spaced relation to the side plate and to the adjacent side of the adjacent panel.

HUGH M. MANLEY.
